RECTIFIER FOR LAMPS.

1,110,644.

Specification of Letters Patent. Patented Sept. 15, 1914.

Application filed August 4, 1910. Serial No. 575,411.

To all whom it may concern:

Be it known that I, JOSEPH C. POLE, a subject of the Emperor of Austria-Hungary, and resident of New York, county of New York, State of New York, have invented certain new and useful Improvements in Rectifiers for Lamps, of which the following is a specification.

My invention relates to systems and means for operating direct current translating devices from an alternating current supply through the intermediation, preferably, of a mercury vapor rectifier. Its object is to provide means for steadyng and controlling current flow in the system, say by providing sustaining inductances in the separate anode circuits of the rectifier, in combination with circuit interrupting elements, enabling them to be used as means for starting the rectifier tube.

A further object of the invention is to provide means for preventing the deleterious action of the tilting magnet usual in this art upon the vapor tube device.

The distinctive features of the invention will be more fully described in connection with the drawings, in which—

Figure 1 represents a diagram of the circuits showing the relation of the various parts; Fig. 2 a simplified sketch, largely diagrammatic, of the connections; and Figs. 3 and 4, respectively, back and front views of a commercial embodiment of the rectifier and related parts.

In the first figure of the drawing, 1 represents the container of the rectifier which may be made of glass, 2 a transformer suitable for adapting the alternating supply to the rectifier, 3, 3 and 4, 4 are respectively coils with iron cores for steadyng and keeping-alive purposes and for starting. A cut out for the circuit of the starting anode is shown at 5, and 6 is the circuit for supplying direct current translating devices 7, 7, 7, for example a direct current mercury vapor lamp, 7^a. The whole apparatus is controlled by the supply switch, 8, and the double pole fuse block, 9. As the particular form of rectifier shown starts by a tilting of the container, an armature, 10, between the poles of the core, 11, of the coils, 4, 4, is pivoted near the center mechanically linked with the container, 1, which is suitably mounted to be tilted in any desired manner. As the magnetic field of the coils,

4, 4, may have a deflecting effect upon the current within the container ordinarily not desirable in this apparatus, I may introduce a magnetic shield 20 between the coil and the rectifier bulb as for example a heavy 60 plate of iron. By this means I am able to prevent the magnetic field of the coils, 4, 4, from exerting a harmful effect upon the action of the rectifier. The operation of the apparatus will be described farther on. 65

In Fig. 2 are shown simplified connections of the apparatus here chosen to represent my invention. The transformer primary winding, 2^a, having several taps at one end of the winding, supplies energy to the secondary winding, 2^b, of the transformer, 2. The terminals of the secondary winding, 2^b, are connected through coils, 3, 3, to the anodes, 12, 12, of the rectifier, the middle part of the secondary, 2^b, is connected 75 through translating devices, 7, 7, 7, and the coil, 4, 4, and the coil of the cut out, 5, to the cathode, 13, of the rectifier. The starting anode, 14, is connected through the contacts of the cut out, 5, to the lead of the 80 anode, 12. In Figs. 3 and 4 these various parts are shown in elevation in an embodiment actually utilized for practical commercial purposes. The apparatus is mounted upon straps, 15, 15, bolted or otherwise supported on a vertical surface at the points, 16, 16, 16. On these straps at the rear are mounted the transformer, 2, near the bottom, the coils 3, 3, in suitable clamps and the coils 4, 4, on a panel, as shown. The 90 coils, 3, 3, happen, in this instance, to have the last layer of the winding only partially filled with wire. On the front of the straps, 15, 15, is mounted a slate or marble panel, 17, carrying the container, 1, which is rotatably mounted on a shaft passing through the panel and also carrying the armature, 10, which armature lies in the field of the cores, 11, 11 of the coils, 4, 4. The cut out, 5, is mounted on the front of the panel, 17. 95 Flexible wires, 18, 18^a, 18^b, and 18^c, are made use of to connect the various electrodes with suitable binding posts mounted upon the panel, 17. The various conductors between the parts including the several taps 105 from the transformer primary winding, 2^a, are shown and need no further description.

The operation is in general, as follows:— Upon closing the supply switch, 8, voltage is impressed upon the primary 2^a, thereby in- 110

ducing voltage in the secondary, 2^b. A circuit is then made through one of the coils, 3, through the contacts of the cut out, 5, to the starting anode, 14. The container is so balanced that when unaffected by the magnetic armature, 10, it hangs in such a position that the electrodes, 13 and 14, are in contact. Under the starting condition now being described, therefore, current will pass from the starting anode, 14, to the cathode, 13 (which electrodes are preferably of mercury), and thence through the cut out coil, 5, the coils, 4, 4, and the translating devices 7, 7, 7, back to the middle of the secondary, 2^b. This current will obviously be alternating and, in virtue of the impedance offered to alternating current by the circuit it traverses, will be relatively limited in volume. The armature, 10, and the apparatus related thereto are, however, so proportioned that this alternating current will be sufficient to tilt the container, 1, sufficiently to interrupt the contact between the starting anode, 14, and the cathode, 13. By the well known action of such a breaking of a current carrying contact within the container, the apparatus will start into operation in virtue of the fact that voltage is impressed upon the anodes, 12, 12, by the secondary, 2^b, provided the breaking of the contact between the electrodes occurs at a favorable moment within the cycle. By the initiation of operation in the rectifier, however, current directly from the anodes, 12, 12, enters the cathode, 13, and traverses the cut out coil, 5, the coils, 4, 4, and the translating devices, 7, 7, 7. This current being rectified is a pulsating direct current and not alternating and hence does not suffer the same opposition from the inductance of its circuit as did the initial alternating current and will therefore greatly exceed the latter in volume. The cut out, 5, is so proportioned that under the influence of this increased current the cut out contacts will be separated thus disconnecting the anode, 14, and interrupting the starting circuit. Should, however, the separation between the electrodes, 13 and 14, caused by the tilting during the starting operation occur at an unfavorable point in the cycle, the tilting current will be interrupted without starting the apparatus and the coils, 4, 4, will consequently be demagnetized and the container, 1, will return to its initial position with the electrodes, 13 and 14, in contact. The remaking of this contact will renew the starting current and the tilting operation will be repeated and so on until the apparatus is started. If, for any reason, this apparatus becomes extinguished, as by the momentary failure of the supply, the starting operation will be renewed by the restoration of normal conditions.

65 An important function of the coils, 3, 3,

is to sustain the current in the circuit of the cathode, 13, and the translating devices, 7, 7, 7, during the periodic intervals of insufficiency in the supply voltage. Either coil will act to prolong the current flow 70 traversing it as its voltage drops until current flow is established by the increase of voltage through the circuit of the other coil, 3. The same action is performed by the coils, 4, 4, which serves to maintain continuance and to steady the current through the cathode, 13, and the translating devices, 7, 7, 7. The coils, 3, 3, serve as well the function of the so-called backing or means for absorbing voltage more or less in proportion 75 to current flow. Such means, as for example resistances, are required with types of apparatus having falling voltage characteristic with increasing current. In my invention the coils, 3, 3, while serving the purpose of 80 backing do so more economically than equally effective resistances in view of the fact that they may absorb voltage more or less in proportion to current flow without a corresponding dissipation of energy. The 85 above described rectifier is especially useful for running direct current apparatus or lamps which require, on common direct current circuits, series resistance to take up the necessary backing voltage, and series inductance for steadyng the current, such as mercury vapor lamps. In this case the inductance coils 3, 3 will replace both series resistance and series inductance of the direct 90 current apparatus so that the apparatus may 95 be kept smaller in size and cheaper.

While I have fully described one embodiment of my invention, other arrangements departing widely therefrom may be utilized and I wish to include and claim all such 100 systems utilizing the novel features disclosed herein.

I claim as my invention:

1. The combination with a single phase supply and direct current translating devices, of an intermediate transformer, a mercury vapor rectifier comprising an hermetically sealed exhausted container, two main anodes, a starting anode and a liquid cathode therein, said two last named electrodes 110 being adapted to make and break contact through movement of the container and separate inductance coils connected between the anodes and the terminals of the secondary of said transformer, of a coil connected by 115 one terminal to the lead of said cathode and by the other terminal to the middle point of said transformer secondary through said translating devices and a magnet coil, and an armature for tilting said container in response to alternating current through said last named coil and a starting circuit to said starting anode shunting said rectifier, together with a cut out having its coil inserted in the lead of said cathode and responsive 120
2. The combination with a single phase supply and direct current translating devices, of an intermediate transformer, a mercury vapor rectifier comprising an hermetically sealed exhausted container, two main anodes, a starting anode and a liquid cathode therein, said two last named electrodes 125 being adapted to make and break contact through movement of the container and separate inductance coils connected between the anodes and the terminals of the secondary of said transformer, of a coil connected by one terminal to the lead of said cathode and by the other terminal to the middle point of said transformer secondary through said translating devices and a magnet coil, and an armature for tilting said container in response to alternating current through said last named coil and a starting circuit to said starting anode shunting said rectifier, together with a cut out having its coil inserted in the lead of said cathode and responsive 130

to current therein, the contacts of said cut out being inserted in said starting circuit.

2. In a system of electrical distribution in which direct current translating devices are fed from an alternating source, through a mercury vapor rectifier having suitable anodes and a cathode, means for steadyng and controlling current flow, said means consisting of separate inductance coils in the leads of said anodes, a tilting coil in the lead of said cathode and a cut out also inserted in the said lead.

3. In a system of electrical distribution in which direct current translating devices are fed from an alternating current source through a mercury vapor rectifier having suitable anodes and a cathode, a starting electrode within the rectifier for breaking down the original negative electrode reluctance, a shunt circuit including the said starting electrode and the main negative electrode and an automatic cut-out for the branch circuit.

4. The combination with a vacuum electric apparatus comprising an exhausted container and suitable electrodes therefor be-

tween which, when of opposite signs, current is adapted to pass, and a tilting magnet in the neighborhood thereof, the field of which is liable, when un-restrained, to have a deflecting effect upon the current in the vacuum apparatus, of a plate or barrier of magnetic material inserted between said magnet and said apparatus.

5. The combination with a vacuum electric apparatus comprising an exhausted container and suitable electrodes therefor between which, when of opposite signs, current is adapted to pass, and a tilting magnet in the neighborhood thereof, the field of which is liable, when un-restrained, to have a deflecting effect upon the current in the vacuum apparatus, of an iron shield inserted between said magnet and said apparatus.

Signed at New York in the county of New York and State of New York this 1st day of August A. D. 1910.
